BY

ATTORNEY

UNITED STATES PATENT OFFICE.

PERCY E. VAUGHAN, OF SAN JOSE, CALIFORNIA.

PUMP.

Application filed June 5, 1922. Serial No. 565,823.

To all whom it may concern:

Be it known that I, PERCY E. VAUGHAN, a citizen of the United States, and resident of San Jose, in the county of Santa Clara 5 and State of California, have invented certain new and useful Improvements in Pumps, of which the following is a specification.

My invention relates particularly to deep 10 well centrifugal pumps.

It is one object of my invention to provide a highly flexible driving means for the pump runners that will not require the use of bearings or other supports throughout 15 its length.

Another object of this invention is to provide means of adjustment for a flexible shaft of the character indicated where by its variation in length due to torsion during 20 operation may be properly compensated for.

Another object is to provide a simple and positive connection between the flexible shaft and the driving mechanism therefor.

25 A further object is to provide a means operable by water pressure developed by the pump for indicating an abnormal tensional strain upon the flexible shaft.

It is a still further object to provide a 30 suitable bearing for the bottom of the shaft to carry the pump runners and shaft when not in operation and during their initial stages when going into operation, together with means for lubricating the same.

35 It is a still further object of my invention to provide a novel form of bearing for the cable.

It is a final object of my invention to 40 provide a pump structure that is simple in construction, quickly and easily assembled in the field with common labor, of comparatively few parts, and economical to manufacture, install and operate.

In the drawing:—

45 Figure 1 is a vertical cross-section through a pump embodying my invention, parts broken away.

Figure 2 is an enlarged section of another 50 embodiment of the cable holding mechanism, parts broken away.

Figure 3 is a section on line 3—3 of Figure 6.

Figure 4 is a section on line 4—4 of Figure 5.

Figure 5 is an enlarged section of the 55 upper cable holding mechanism, parts broken away.

Figure 6 is a section through the coupling 60 of the cable to the pump bowl assembly shaft, parts broken away.

Figure 7 is another embodiment of mounting a bearing upon the cable to work in a bearing formed integrally with the discharge casing, parts being broken away.

Figure 8 is a cross-section through the 65 pump bowl and runner assembly showing my improved manner of indicating the pressure in the pump, parts being broken away.

Referring more particularly to the drawing, I show at 1 the usual deep well casing 70 construction and at 2 is shown the discharge column rising from the bearing bowl 3 upwardly to the discharge head 4. Bolted to discharge head 4 is the pulley bearing member 5 which has an annular depression 6 75 formed in a false bottom member as 7, while at 8 is shown a series of cap screws threaded into the bottom 7 and extending upwardly into depression 6 so as to adjust the roller bearing portion 9. This adjustment being 80 made through the openings 10 in the walls of bearing member 5 as shown. At 11 is shown a second annular depression formed in the wall 12 of said bearing portion 5, a roller bearing 13 fitting therein as shown, 85 while at 14 and 15 is an opening in the bottom 7 and in the base portion through which a long annular member 16 passes as shown.

The upper portion of member 16 is 90 threaded as at 17 and has the bearing support 18 slidably mounted thereon by means of key 19 as shown, while set in the lower faces of support 18 is a bearing portion 20 in alignment with bearing portion 9 as 95 shown. The upper portion of support 18 has a bearing portion 21 set therein in alignment with bearing portion 13 while at 22 is shown a member threaded to screw over the bearing support member 18 and supporting 100 an adjusting nut 24 as shown.

Above adjusting nut 24 is secured the driving pulley 26 by means of the key 25 in member 16, while at 27 is a hexagon headed portion set into the upper end of 105 member 16, and having a series of upstanding portions as 28, these being tapered and threaded to receive a nut as at 29. The

inner surface of these taper threaded portions 28 having inwardly and upwardly pointing projections 30 as shown.

Passing through the center of portion 16 is a flexible wire cable 31 which is held securely at its upper end by the tightening up of nut 29 which causes the tapered portions 28 to draw inward thus tightening up on cable 31 and at the same time the projections 30 are forced into the cable and their upwardly slanting points keep the cable from being pulled out from a downward strain as is readily apparent.

The cable 31 passes down through the discharge casing 2 and into a tubular member 32 which acts as a shaft for the bowl assembly, the lower end of said cable having a solid portion 33 threaded thereon and having a concave surface as 34 in the end thereof. The lower bearing 35 of the suction section is formed with a convex upper portion 36 of such proportions as to fit the concave portion 34 as shown, which is screwed into a supporting member 37, while at 38 is a small orifice passing through member 35 to aid in lubricating the same when the pump is started.

In Figure 6 I show another embodiment of means for connecting the cable 31 to the regular solid bowl assembly shaft as shown at 39 which has its lower end concaved out as at 40 to fit the bearing portion 36 as shown in Figure 1. The shaft 39 is threaded into a collar member 41 which is tapered out at its upper end as at 42 to receive tapered members 43 having inwardly and downwardly projecting teeth as at 44 which grip the cable 31 when the cap member 45 is screwed down upon the same as shown. This construction effectually preventing the cable from being pulled out when under the strain of actual operation.

In Figure 2 is shown another embodiment of supporting the upper end of cable 31 from that shown in Figure 1. Here I show a solid member 46 passing upwardly through the members 14-15-18-22 and threaded to take nut 24 as shown at 47 instead of the hollow member 16 shown in Figure 1. The cable 31 being securely mounted in member 46 by means of the above described tapered portions 43 with their now inwardly and upwardly projecting prongs 44 and the cap 45 as shown. The keyway and key 25 being made to allow the solid portion 46 to be raised or lowered as shown.

As disclosed in the drawing the shaft member 16-46 is supported upon roller bearings 9-20 and the radial thrust is taken up by the bearings 13-21. The pulley 26, nut 24, members 22-18-16 all rotating together and thus turning the impellers in the bowl assembly by means of the flexible wire connecting cable 31 which is perfectly free from bearings of any kind from the dis-

charge head to the pump bowl assembly as shown.

As is shown at 47 the bowl bearing portion is recessed out for a distance and then another recess 48 is made below the first mentioned recess as shown. A small orifice 49 connecting recess portion 47 with the interior of chamber 50 of said bearing which is in turn connected to a pipe 51 by cored hole 52 passing to the said pipe as shown.

The runner 53 of said bowl has an upwardly flange 54 which is a sliding fit in the recess 47 of the bearing portion as shown, the whole being so formed that at normal pump speed the upper edge of flange 54 is just below the orifice 49 as shown in Figure 8. When this condition prevails a water pressure is created in chamber 50 by means of the orifice 49 and the space between the runner and the bearing which thus causes the water to be forced up through the pipe 51 to the surface as shown at 55 where the water runs out of the open end of the pipe. During the operation of the pump, however, if the speed should increase for any reason this increase in speed would cause the flexible cable 31 to be drawn up tighter due to the increased torsional strain and this would raise the runner 53 so that the flange 47 will raise up over the orifice 49 and cut off the water supply to the pipe 51 thus causing the overflow from the end 55 to cease. This serves as a warning to the operator that the cable 31 is too tight and he loosens the screws 8 in the pulley assembly 5 which allows the bearing portion 9 to lower thus lowering the entire bearing assembly which again brings the impeller to the normal running position as indicated by the starting of the water overflow from the pipe 51 as at 55.

By the use of a flexible cable in place of a solid shaft I can do away with all bearings in the discharge casing column as well as the necessary lubrication system which solid shafts require. Having provided means for overcoming the slight variations in cable lengths due to more or less torsion when the same is in operation and having also provided accurate means for indicating when this condition prevails as well as means for supporting the lower end of the driving cable mechanism during the starting operation and lubricating the same during the operation of the pump as shown in the drawing I believe that I have provided a pump structure that, is simple in construction, quickly and easily assembled in the field with common labor, of comparatively few parts and economical to manufacture, install and operate.

In the embodiment shown in Figure 7 a member 56 is shown made preferably of babbitt and cast on cable 31 as an integral part thereof and formed with a true cylin-

drical outer surface. At 57 is shown a bearing supported by discharge casing 2. The member 56 is so proportioned with relation to bearing 57 that any movement of the cable through the bearing while the pump is in operation will not reduce the amount of bearing surface of member 56 presented to the bearing 57.

It should be further pointed out that in its simplest form the invention contemplates a structure wherein the impeller may have sufficient movement to obviate the necessity of providing adjusting devices or pressure indicators as above disclosed.

15 It is to be understood, of course, that while I have herein shown and described the preferred embodiments of my invention that changes in form, proportion, construction, method of operation and arrangement 20 of parts may be made within the scope of the appended claims.

I claim:-

1. In combination a pump head, a cable suspended therefrom, and an impeller operatively mounted upon said cable.
2. In combination, a pump head, a pump bowl assembly including an impeller suspended therebelow, a cable drive shaft connecting said head and impeller, and means 30 for adjusting said cable with relation to said head and impeller.
3. In combination, a pump head, a pump bowl assembly including an impeller suspended therebelow, a cable drive shaft connecting said head and impeller, and means 35 for indicating a variation in the length of said cable due to the torsional strains thereon.
4. In combination, a pump head, a pump bowl assembly including an impeller suspended therebelow, a cable drive shaft connecting said head and impeller, a pressure chamber adjacent said impeller, impeller operated means for opening and closing 45 said chamber, and a conduit extending upwardly a distance from said pressure chamber.
5. In combination, a pump head, a pump bowl assembly including an impeller suspended therebelow, a cable drive shaft connecting said head and impeller, a pressure chamber in a pump bowl adjacent said impeller and provided with an intake port, means carried by said impeller for closing

said port when raised and opening said port when lowered, and a conduit extending upwardly a distance from said pressure chamber.

6. In combination, a pump head, a pump bowl assembly, including an impeller suspended therebelow, a tubular stub shaft revolvably mounted in said head, a cable drive shaft connected to said impeller and passing through said stub shaft, means for securing said cable in said stub shaft, and means for 65 adjusting said stub shaft with relation to said head.

7. In combination, a pump head, a pump bowl assembly including an impeller suspended therebelow, a tubular stub shaft revolvably mounted in said head, a cable drive shaft connected to said impeller and passing through said stub shaft, means for adjusting 70 said stub shaft with relation to said head, and adjustable means for securing said 75 cable in said stub shaft.

8. In combination, a pump head, a pump bowl assembly including an impeller suspended therebelow, a stub shaft mounted in 80 said head, thrust bearings inserted between said stub shaft and head, a vertical adjustment for said thrust bearings, and a cable drive shaft connecting said stub shaft and impeller.

9. In combination, a pump head, a pump bowl assembly including an impeller suspended therebelow, a stub shaft revolvably mounted in said head, a stub shaft mounted in said impeller, a cable drive shaft connecting 85 said stub shafts, and means for varying the spacing of said stub shafts.

10. In combination, a pump head, a pump bowl assembly including an impeller suspended therebelow, a cable drive shaft connecting said head and impeller, a bearing 90 element mounted on said cable, and a bearing operatively arranged with relation to said element.

11. In combination, a pump head, a pump bowl assembly including an impeller suspended therebelow, a cable drive shaft connecting said head and impeller, a bearing element mounted on said cable, and forming 95 an integral part thereof, and a bearing operatively arranged with relation to said 105 element.

PERCY E. VAUGHAN.
